United States Patent Office.

DANIEL WITT AND AARON WAIT, OF HUBBARDSTON, MASSACHUSETTS.

Letters Patent No. 97,012, dated November 16, 1869.

IMPROVED HANDLE FOR BRUSHES, CARDS, &c.

The Schedule referred to in these Letters Patent and making part of the same.

To all whom it may concern:

Be it known that we, DANIEL WITT and AARON WAIT, both of Hubbardston, in the county of Worcester, and State of Massachusetts, have invented a new and useful Handle for Brushes, Cards, &c.; and we do hereby declare the following to be a clear and exact description of the same, reference being had to the accompanying drawing, making part of this specification, in which—

Figure 1 is a side view of the handle, and Figure 2 shows its application.

Similar letters of reference indicate corresponding parts in the two figures.

Our invention consists in forming an opening in one end of the body of a cast-metal connection, which opening is to receive a handle as ordinarily, but the other end is provided with jaws or forks of different dimensions, so that a long bearing is formed to receive the strain, which is counteracted or restrained by the short jaw, whereby a simple article of manufacture is produced, as will be hereinafter more fully described.

In order that others skilled in the art to which our invention appertains, may fully understand and use the same, we will now proceed to describe it.

In the drawing—

A represents an ordinary handle;

B, the head of a brush, curry-comb, card, or other like article; and

C, the connection between the two.

This connection is constructed of cast-metal, and formed with a socket, a, at one end; and forks b b' at the other end.

The socket a is made to receive one end of the handle A, in any well-known manner.

The forks b b' are intended to grasp the head B, and form a firm bearing or support for the latter, and thereby produce a strong joint, which is further increased by screws, rivets, or other fastenings passing through the head and one or both forks.

The head may be cut out, to "let in" the forks, and thus the projection of the latter beyond the surface of the head is prevented, which is especially desirable on the lower face of the head, as seen in fig. 2.

The advantages of the connection are, its cheapness and strength, its simplicity and practicability.

Should the head break or the brush wear out, the connection is still useful, and is readily applicable to new brushes, &c.

In cards, it has been customary to slit the wooden handle, and thus secure the head, but this mode is expensive, owing to the liability of breakage, and the consequent necessity of new handles.

Having thus described our invention,

What we claim as new, and desire to secure by Letters Patent, is—

The lower fork b', extended beyond the other, to form a long bearing to receive the strain which is counteracted by the short fork b, when the two forks are cast with a body, C, having a socket at the opposite end, and the parts form a cast-metal connection, as a new article of manufacture.

To the above, we have signed our names, this 15th day of April, 1869.

DANIEL WITT.
AARON WAIT.
